UNITED STATES PATENT OFFICE.

GEORGE M. BAKER AND WILLIAM ABBOTT, OF ESPY, PENNSYLVANIA.

STEP-LADDER.

SPECIFICATION forming part of Letters Patent No. 285,949, dated October 2, 1883.

Application filed May 7, 1883. (No model.)

To all whom it may concern:

Be it known that we, GEORGE M. BAKER and WILLIAM ABBOTT, citizens of the United States, residing at Espy, in the county of Columbia and State of Pennsylvania, have invented certain new and useful Improvements in Step-Ladders, of which the following is a specification, reference being had therein to the accompanying drawings.

10 This invention relates to step-ladders of that class to which a shelf is connected by suitable devices in such manner that it will fold up or open out automatically with the ladder when it is opened or closed, the peculiarities of which will be hereinafter more particularly described.

15 In the accompanying drawings, making part of this specification, Figure 1 represents a vertical section of our invention; Fig. 2, a perspective of the shelf and its connections, and Fig. 3 a detached view of the top of the ladder.

20 In the figures, A represents the ladder-frame which carries the steps, and B the bracing and supporting frame, hinged to the frame A, near its upper end, both frames being constructed in any of the well-known and usual ways and forms.

25 D represents the top or platform of the ladder, one end of which may be extended beyond the frames, as shown, to afford additional room upon the same.

30 I represents the folding shelf, which is bolted or otherwise properly secured upon the upper side of a bar, F. The bar F is firmly secured to a shaft, H. The shaft H is placed between the two side pieces of the frame B, and is provided with arms or trunnions e e, which have suitable bearings in said sides. A long slot or 35 opening is formed in the inner end of the bar F, and at the rear end of said slot the bar is provided with a miter-bevel. The forked ends

of the bar F are mitered, as seen at a a, Fig. 2. E represents a bar, through which, near its outer end, passes a rod, G. The ends of this 45 rod pass through and have their bearings in the side pieces of frame A.

M represents a tongue upon the inner end of bar E, which is inserted and pivoted, as seen at d, in the slot in bar F. This tongue 50 has mitered shoulders and a mitered end, the mitered end fitting against the miter on bar F, at the inner end of the slot, and the mitered shoulders fitting against the mitered ends a a 55 of bar F when the two bars are in line, as seen in Fig. 1. The mitered portions of the two bars fitting snugly together and securely held in position by the pivot d, a lock-joint is formed which not only insures permanency to the shelf, but prevents the two parts of the 60 ladder from closing together as long as there is weight upon the shelf or the two bars are in line. When it is desired to close the ladder, the joint between the bars is buckled down, and the shelf, making a partial rotation, folds 65 in with the frames, its outer end lying beneath the top or platform of the ladder.

Having thus fully described our invention, what we claim as new, and desire to secure by Letters Patent, is—

70 The combination of the ladder-frame A and supporting-frame B with the shelf I, shaft H, bars E and F, and the rod G, bar F being slotted and bar E provided with a tongue which is pivoted in the slot, the two bars being mitered substantially in the manner and for the purpose set forth.

75 In testimony whereof we affix our signatures in presence of two witnesses.

GEORGE M. BAKER.
WILLIAM ABBOTT.
